(57) CLAIM

The ornamental design for an above ground collapsible garden bed, as shown and described.

DESCRIPTION

FIG. 1 is a front and side perspective view of a collapsible garden bed showing the new design.

FIG. 2 is a bottom perspective view thereof.

FIG. 3 is a back and side perspective view thereof; and,

FIG. 4 is a top perspective view thereof.

The broken line showing of the garden bed is included for the purpose of illustrating portions of the article and forms no part of the claimed design.

1 Claim, 4 Drawing Sheets

FIG. 1

FIG. 4
